[57] ABSTRACT

A header assembly is adapted to be mounted on top of a partition wall and connected to an air outlet opening in a suspended ceiling system. The header has air divider means which will direct air to either side of the partition. The air divider is a simple X-shaped air deflector which alternately directs air to either side of the X-shape.

PARTITION ADAPTOR AND VENTILATING AIR DIVIDER

BACKGROUND OF THE INVENTION

1. Field of the Invention

The invention relates to a header assembly for dividing air from an elongated ceiling duct disposed above a partition wall.

2. Description of the Prior Art

U.S. Pat. No. 3,319,558 is directed to a partition wall header with an air divider structure 26 and the apparatus therein is adapted to be mounted on top of a partition wall and the header is connected with the air outlet opening in the support system of the suspended ceiling. Air is directed into the header and partition 26 divides the air and passes it to either side of the partition wall.

U.S. Pat. No. 3,401,623 discloses an air divider which is Y-shaped and directs air to either side of an air outlet passageway.

The prior art is replete with examples of air diffusers. There also exist air dividers which can be used in conjunction with partition walls. However, none of the prior art structures uses a very simplified type of air divider which also provides the additional advantage of deflecting sound so that sound will not be passed from one portion into different portions of a partitioned area.

SUMMARY OF THE INVENTION

The invention herein is composed of the header structure and an air divider therein. The header structure is generally box-shaped and extends along the partition wall. An opening in the top of the header communicates with the air outlet opening in the suspended ceiling system. Apertures on the side of the header will distribute air to either side of the partition wall. Within the header there is positioned an air divider which will direct the air to either side of the partition wall while at the same time reflect sound so that it will not be transmitted from one partitioned area into another partitioned area. The air divider is basically X-shaped and is composed of two components which are so cut out that they will intermesh together to form the X configuration.

BRIEF DESCRIPTION OF THE DRAWING

FIG. I is a sectional view of a partition with the header connected between the top of the partition and the ceiling air distribution system;

FIG. II is a perspective view of the header and air divider structure; and

FIG. III is a perspective view of the divider structure.

DESCRIPTION OF THE PREFERRED EMBODIMENT

The header assembly may be used with any typical suspended ceiling air distribution and diffusion system, as for example that shown in U.S. Pat. No. 3,319,558. Referring to FIG. I, there is shown a typical room divider structure wherein a partition 2 is used to divide an area into two separate areas. Normally positioned above the partition is the air diffuser system 4 of the suspended ceiling system. The suspended ceiling system 6 is conventional in the art and is basically composed of a support grid structure with ceiling boards supported therein. Some of the support grid structures are provided with air outlet openings. Air is fed to a

boot structure 8 and the boot structure is fastened to the top of the air diffuser system 4 so that conditioned air can be fed through the air diffuser system 4 into the area underlying the suspended ceiling system. Often partitions are tied into the air diffuser system to provide a point at which the top of the partition can be anchored to the overlying ceiling.

An air header and diffuser assembly 10 is placed on top of the partition and engages the air outlet opening 10 of the air diffuser system 4.

Oftentimes the header structure is rigidly fastened to the partition and the air diffuser system 4 so as to lock the top of the partition to the overlying ceiling in the region of the air diffuser system. As shown in FIG. II, the header and air diffuser assembly 10 is composed of a box-like header structure 12 which has a small opening at its upper side 14. The opening 16 is provided with flanges 18 which pass into the outlet opening of the air diffuser system 4 so that conditioned air may be channeled from the boot 8 to the air diffuser system 4 and into the header structure 12. Slots 20 are provided on the side of the header structure at staggered intervals to provide an outlet for the conditioned air from the header 12. Within the header structure 12 there is positioned an air divider 22 which directs the air coming in through opening 16 to the slots 20 which are positioned on either side of the header structure 12.

In FIG. III, there is shown the air divider structure 22. This structure is basically an X configuration. A plurality of flat pieces of material 24 are formed with notches 26 therein. This then generates a serrated top edge structure which has the notches 26 and tab-like structures 28. A second piece of material is formed similar to the first piece of material except that notches are provided opposite the tabs 28 of the first piece of material and vice versa. Therefore, the two pieces of material may be engaged in a configuration which on cross section will appear to be an X. While the bottom two legs of the X will extend for the full length of the assembly, the top two legs of the X are actually formed from staggered short sections of the tab-like structures 28. Naturally, adjacent each tab-like structure there is a notch 26. Air coming from the opening 16 of the header structure 12 will strike a tab 28 and be deflected into and through the adjacent notch 26. Since the tabs are staggered down through the length of the divider, it is obvious that a certain portion of the air will be deflected to either side of the header structure 12 and will pass out through slots 20 on either side of the header structure. Also, the existence of the X structure with the staggered notches and tabs will result in a minimizing of noise from one side of partition 2 to the other side thereof since the X structure obstructs a direct acoustical path through the header structure 12. The header structure could be used with the tab and notch structure so arranged that more or less air could be directed to one or the other side of the partition 2.

What is claimed is:

1. A header assembly for dividing conditioned air from an elongated air outlet duct to two sides of a room partition wall disposed beneath the duct comprising, a box-like header structure which is positioned on top of the partition wall and which has an air inlet opening in its upper side for receiving conditioned air from the elongated duct, within the header structure there is positioned a generally X-shaped air divider means which along its length will alternately direct air to either side

of the air divider and out of openings on the side wall of the header structure, said air divider means is composed of two pieces of material which have at their upper edges alternate tab and slot structures which will mesh together to hold the two pieces of material in an X configuration with the tabs of one piece of material being inserted into the notch structure of the interlocking second piece of material.

2. The header assembly of claim 1 wherein the box-like header structure has two side walls containing the openings through which air passes after being directed by the air divider, said air divider being placed within the box-like header with the lower edges of the two pieces of material forming the air divider being positioned within the header structure with the bottom of

10

15

the two pieces of the air divider being placed adjacent the bottom to the side wall of the header structure.

3. The header assembly of claim 2 wherein the upper edges of the two pieces of material forming the air divider have a plurality of alternate tab and slot structures which mesh together to hold the two pieces of material in the X configuration, said tabs are positioned closely adjacent the air inlet opening of the header structure and the tabs direct the inlet air towards either side of the header structure, while the lower portion of the two pieces of material forming the air divider directs the air out of the openings on the side walls of the header structure.
